UNITED STATES PATENT OFFICE.

GIFFORD W. COOLEY, OF PLAINFIELD, NEW JERSEY.

DESIGN FOR A DOLL.

48,221.

Specification for Design.

Patented Nov. 30, 1915.

Application filed August 30, 1915. Serial No. 48,120. Term of patent 7 years.

To all whom it may concern:

Be it known that I, GIFFORD W. COOLEY, a citizen of the United States, residing in Plainfield, county of Union, and State of New Jersey, have invented a new, original, and ornamental Design for a Doll, of which the following is a specification, reference being had to the accompanying drawing, forming a part thereof.

In the drawing Figure 1 is a front elevation and Fig. 2 is a side elevation of a doll, showing my new design.

I claim:

The ornamental design for a doll, as shown.

GIFFORD W. COOLEY.

Witnesses:

GEO. A. HALLOCK,
FREDERICK T. JACOBS.
